SURFACE MAINTENANCE MACHINE

Lloyd D. Fortman and Joseph G. Kasper, Golden Valley,
and John N. Polivka, Hopkins, Minn., assignors to
Tennant Company, Minneapolis, Minn.

Filed Aug. 3, 1971, Ser. No. 168,791

Term of patent 14 years

Int. Cl. D15—05

U.S. Cl. D49—9.1

FIG. 2

FIG. 1

FIG. 3

FIG. 4

FIG. 5

FIG. 6

FIG. 7

FIG. 1 is a right side elevational view of a surface maintenance machine embodying our new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is a rear perspective view of a modified form of our new design wherein an operator's seat has been added.

We claim:

The ornamental design for a surface maintenance machine, substantially as shown and described.
